UNITED STATES PATENT OFFICE.

HOMER J. WADDELL, OF BALTIMORE, OHIO, ASSIGNOR, BY DIRECT AND MESNE ASSIGNMENTS, TO THE GAS APPLIANCE MANUFACTURING CO., OF BALTIMORE, OHIO, A CORPORATION OF OHIO.

DIAPHRAGM STRUCTURE.

Application filed September 2, 1925. Serial No. 53,994.

This invention relates to improvements in diaphragms of the type employed in connection with gas flow recording meters, and an object of the invention is to provide a diaphragm especially adapted for this service and embodying improved features of construction and design by means of which the life of the diaphragm is considerably prolonged, as compared to the forms hitherto used and wherein the operation of the diaphragm is substantially uniform throughout its life so as to preserve the accuracy and reliability of the recording meter in which it is embodied.

With these and other objects in view, as will appear as the description proceeds, the invention consists in the novel features of construction, combinations of elements and arrangements of parts hereinafter to be fully described and pointed out in the appended claims.

In the accompanying drawing:

Figure 1 is a vertical sectional view taken through a portion of a gas flow recording meter, and illustrating the improved diaphragm structure comprising the present invention in an operative position therein,

Figure 2 is a vertical transverse sectional view on the plane indicated by the line 2—2 of Figure 1,

Figure 3 is an enlarged vertical sectional view of a portion of the diaphragm structure, illustrating the latter in one extreme of its operating positions,

Figure 4 is a similar view disclosing the diaphragm at the extreme of its other operating positions.

Referring more particularly to the drawings the numeral 1 designates generally the casing of a gas flow recording meter and in this instance the casing is of the type employing cast metal outer walls, in contrast to sheet metal casings employed upon gas meters used in indoor service. The casing as shown comprises a drum shaped body section 2 and one or more cover sections 3, the sections 2 and 3 being provided with adjoining out-turned flanges 4, between which is situated and clamped the diaphragm structure 5 comprising the present invention. This structure is disposed so as to divide the casing into spaced gas flow chambers 6 and 7 which by means of the cus-

tomary valve mechanism and ports (not shown) are in communication with the recording housing 8 disposed at the upper side of the casing. Since the specific construction of meters of this type is common and well understood, it is not deemed necessary or advisable to enter into a further detail description of their construction and operation, since the present invention is concerned with the design of the diaphragm structure and does not effect in any other way the general operation of meters of this type.

In the present instance the diaphragm structure is formed to comprise essentially inner, outer and intermediate sections 9, 10 and 11 respectively, and, as shown, the inner section is formed preferably from sheet metal so as to present a rigid, inflexible yet light-weight body to the gas pressures within the casing. The peripheral edge of the section 9 is provided with an annularly grooved flange 12 extending longitudinally with respect to the axis of the diaphragm structure. The intermediate section of the diaphragm structure is preferably formed from a tough, durable yet flexible material such as leather, which remains uneffected by prolonged contact with the chemical constituents of the gas flowing through the meter. The inner peripheral edge of the intermediate section is in-turned as at 13 so as to engage with the outer surface of the flange 12 and is secured thereto in this instance by means of a tautly wrapped binding cable 14, which serves to draw the inner edge of the intermediate section into the annular groove of the flange 12 and to securely retain the same in a seated and immovable position therein. The axial portion of the inner section 9 of the diaphragm is connected as at 15 with the usual recording operating frame 16, so that as the inner section of the diaphragm pulsates, in response to unbalanced fluid pressures on opposite sides thereof, the frame 16 will be moved to operate the recording mechanism in the usual manner.

In prior forms of diaphragm structures it has been customary to extend the flexible leather section so that the outer peripheral portion thereof is clamped between the body and cover sections 2 and 3 of the casing. In

other words the leather material, constituting the flexible section is extended to contact directly with the inner faces of the flanges 4, so that upon the tightening of the 5 fastening elements 17 used in uniting the cover section with the body section of the casing, the leather is placed under compression to retain the diaphragm in place. Observation has disclosed that when the leather 10 or flexible section of the diaphragm is thus clamped and held in place, the pressures applied thereto and the chemical action of the metal on the leather, results in the rapid deterioration of the flexible section of the 15 diaphragm, causing said flexible section to harden and to become relatively brittle, not only adjacent those portions located between the flanges 4 but also well into the inner portions of the flexible section of the diaphragm. 20 It was well understood and very common in this art prior to the discovery of this invention to impregnate the leather of the diaphragm with a limited amount of oil or other lubricant, sufficient to protect the 25 leather from rapid deterioration by prolonged contact with the gas, and considerable effort has been made to devise the best quality of oil for this purpose, and yet in this type of meter where the diaphragm is 30 common to two measuring chambers, the leather is necessarily stretched to its full extent, which causes the outer part of the leather, i. e., the part adjacent to the metal casing to fold and unfold, and this constant 35 folding and unfolding will cause the lubricant to escape through the part of the leather clamped between the casing members, unless proper provision is made to prevent that. Furthermore, a certain amount of capillary 40 attraction in the type of diaphragm heretofore used, has permitted the oil to escape, but with this improved arrangement and method the lubricant is retained within the measuring chamber and is not exposed to the outside atmosphere, thereby minimizing the 45 evaporation and preventing the action of the capillary attraction. If this lubricant is not retained the leather will necessarily tighten up, which will tend to shorten the stroke of 50 the diaphragm, thereby rendering the instrument inaccurate and unsatisfactory, beside shortening the life of the diaphragm itself. As a result of this condition, and also due to the constant pulsating action of the diaphragm, the leather breaks and cracks so 55 that gas flow occurs between the chambers 6 and 7 through the diaphragm structure, resulting thereby in gas flow from the meter which has not been recorded. To overcome 60 this condition I provide the inflexible outer section 10 of the diaphragm, the latter in this instance consists of a metallic ring which conforms to the outside diameter and shape of the flanges 4, the said ring being perforated as at 18 so as to align with the perfora-

tions in the flanges 4 provided for the reception of the fastening elements 17. Further, the ring is provided with an arcuate port 19 by means of which gas flow is permitted in the customary channels through the casing. 70 The inner periphery of the ring is formed with an in-turned axially disposed flange 20 provided with an annular groove in which is positioned the outer peripheral edge of the flexible intermediate section 11 of said 75 diaphragm. A binding cable 21 passes around the section 11 and frictionally holds the latter in secured relation within the annular groove provided in the flange 20.

In view of the foregoing it will be seen 80 that the present invention provides a diaphragm particularly adapted for use in connection with gas flow recording meters wherein but a minimum of flexible material is utilized in the construction thereof. Reference to flanges 3 and 4 would disclose that the flexible section of the diaphragm is only of such area as to provide for the proper stroke of the diaphragm. The remainder of the diaphragm is of metallic construction 85 and is therefore not subject to the same wear and deterioration as is the flexible section. One of the outstanding features of the present design is the marked reduction in the amount of leather utilized, as hitherto it has 90 been customary to extend the leather over the full area of the diaphragm. In the present instance only but a small proportion of the area of the diaphragm is utilized by the flexible section. Again, by the manner of 100 connecting the inner and outer edges of the flexible sections with the flanges 12 and 20 complete freedom and play of movement is given to the flexible section so that the latter will flex and bend naturally and easily, without strain or distortion which is so strongly characteristic of previous forms of diaphragms wherein the leather is directly clamped to the casing. Moreover, by the provision of the metallic outer section of 110 the diaphragm the present invention eliminates premature hardening of the leather, avoiding its cracking, wrinkling and the general breaking down of its pliable and flexible form. It is in this respect particularly that the present invention, by the inclusion of the metallic outer section, overcomes one of the prime difficulties faced by 115 previous designs.

What is claimed is:

1. In a gas meter, a casing including a diaphragm chamber open at one end, a removable cover section closing the open end of said chamber, a diaphragm structure formed to occupy said chamber and embodying an outer ring member of rigid material secured between the adjacent walls of said casing and cover section, said ring member being formed to include an in-turned flange lying closely adjacent to and parallel with 120

125

130

the inner walls of said diaphragm chamber, an inner disk member of rigid material formed to include a peripheral flange, and a body of flexible connecting material secured to the flanges of said ring and disk members, said material possessing but sufficient area to admit of the employment of a disk member of large diameter and displacement commensurate with the length of the operating stroke of the disk member from one side to the other of the plane of the outer ring member.

2. In a gas meter, a casing including a diaphragm chamber open at one end, a removable cover section closing the open end of said chamber, a diaphragm structure formed to occupy said chamber and embodying an outer ring member of rigid material secured between the adjacent walls of said casing and cover section, said ring member including an inturned flange extending away from said cover section and lying closely adjacent to and parallel with the inner wall of said diaphragm chamber, an inner disk member of rigid material formed to include a peripheral flange, and a body of a flexible connecting material secured to the respective flanges of said ring and disk members and serving to movably support said inner disk member to admit of travel thereof to one side or the other of the plane of said outer ring, said body of flexible material possessing limited area to admit of the employment of a disk member of large diameter and displacement but not so limited as to effect detrimentally the desired length of the operating stroke of said disk member.

3. In a gas meter, a casing including a diaphragm chamber open at one end, a removable cover section connected with said casing and closing the open end of said chamber, a diaphragm structure formed to

occupy and transversely divide said chamber, said diaphragm structure embodying a cylindrical ring member of a rigid material provided with a flange secured between the adjacent walls of said casing and cover section, said ring member possessing an inside diameter whereby the inner peripheral portion thereof terminates immediately adjacent to the wall of said diaphragm chamber,

an inner disk member, and a body of a flexible connecting material secured to the outer peripheral portion of said disk member and the outer peripheral portion of said ring member, the area of said flexible material being limited to admit of the employment of a disk member of maximum diameter.

4. In a gas meter, a casing including a diaphragm chamber open at one end, a removable cover section closing the open end of said chamber, a diaphragm structure formed to occupy said chamber and embodying an outer ring member of a rigid material clamped between the adjacent walls of said casing and cover section, said ring member including an inturned flange disposed closely adjacent to and parallel with the inner wall of said diaphragm chamber, said flange extending in a direction away from said cover section, an inner disk member of rigid material formed to include a peripheral flange extending toward said cover section, and a body of a flexible connecting material secured to the flanges of said ring and disk members, said material possessing but sufficient area to admit of the employment of a disk member of maximum diameter and displacement but without interfering with the operating stroke of said disk member.

In testimony whereof I affix my signature.

HOMER J. WADDELL.
